D. D. BIGELOW, OF WHITE HOUSE, NEW JERSEY.

Letters Patent No. 86,053, dated January 19, 1869.

IMPROVED RAILWAY-RAIL CHAIR.

The Schedule referred to in these Letters Patent and making part of the same.

To all whom it may concern:

Be it known that I, D. D. BIGELOW, of White House, in the county of Hunterdon, and in the State of New Jersey, have invented certain new and useful Improvements in "Railroad-Chairs;" and do hereby declare that the following is a full, clear, and exact description thereof, reference being had to the accompanying drawings, and to the letters of reference marked thereon.

The nature of my invention consists in so constructing a "chair" of one piece of metal, that it will form a base for the ends of the rails, and with side-braces on each side of the rail, of one piece of metal, and securing the same and the rails by spikes, which pass at the sides of the side-braces, grasp the web of the rail, and pass through openings in the body of the chair.

In order to enable others skilled in the art to make and use my invention, I will now proceed to describe its construction and operation, referring to the annexed drawings, which form a part of this specification, and in which—

Figure 1 is a side elevation of my railroad-chair attached to the rails;

Figure 2, a cross-section of the same; and

Figure 3, a plan view of the iron plate, cut so as to form the chair.

A, fig. 3, represents a plate of iron, cut with projections *a a* at the ends, for convenience in entering the rail.

This plate is cut, as shown in fig. 3, forming the

spike-holes *b b*, the guard *c*, lips *d d*, and holes *e e*, for the spikes or bolts to fasten the chair to the rails. It will be seen that this plate, when so cut, and the guards and lips turned or bent up, is still in one piece, and not cut so as to be disconnected at any place.

The guards and lips, when turned up, are bent so as to correspond with the shape of the rails *B B*, and may be secured by bolts passing through the holes *e e*. These bolts, when used, prevent the rails from running on a double track, or any side motion, and do not sustain any weight, as some other chairs now in use. This chair is so formed as to sustain the weight independently of the bolts.

Having thus fully described my invention,

What I claim as new, and desire to secure by Letters Patent, is—

The chair herein described, made of a flat piece of metal, with side-braces *c c*, and with openings *b b*, so that the rails are secured by the spikes, which pass through these openings, and the base, *A*, of the chair, and grasp the web of the rails, all substantially as set forth.

In testimony that I claim the foregoing, I have hereunto set my hand, this 14th day of September, 1868.

D. D. BIGELOW.
